UNITED STATES PATENT OFFICE

150,627

DESIGN FOR A STICKPIN OR SIMILAR ARTICLE

George S. Krajian, Hataitai, Wellington,
New Zealand

Application November 15, 1947, Serial No. 142,558

Term of patent 14 years

(Cl. D45—19)

To all whom it may concern:

Be it known that I, George S. Krajian, a citizen of the Lebanese Republic, residing at 83 Moxham Avenue, Hataitai, Wellington E. 2, New Zealand, have invented a new, original, and ornamental Design for a Stickpin or Similar Article, of which the following is a specification, reference being had to the accompanying drawing, forming a part thereof.

In the drawings:

Fig. 1 is a front view of the stickpin or similar article, showing my new design with the propeller inclined to the vertical;

Fig. 2 is a side view thereof; and

Fig. 3 is a top view with the propeller rotated into a vertical position.

The dominant features of the design reside in the portion of the pin shown in full lines.

I claim:

The ornamental design for a stickpin or similar article, substantially as shown and described.

GEORGE S. KRAJIAN.
